BUILDING SLAB, PLATE, OR MEMBER

Filed Oct. 1, 1926

*By: Marks & Clark
Atys*

UNITED STATES PATENT OFFICE.

HANS FRITZ, OF INNSBRUCK, AUSTRIA, ASSIGNOR TO MATHMAH GESELLSCHAFT MIT BESCHRÄNKTER HAFTUNG, OF WIESBADEN, GERMANY; A COMPANY OF GERMANY.

BUILDING SLAB, PLATE, OR MEMBER.

Application filed October 1, 1926, Serial No. 138,991, and in Austria October 15, 1925.

This invention relates to improvements in building slabs, plates or members which are of simple construction and of great strength and carrying capacity and are well suited 5 not only for erecting walls and ceilings, but also for roof- and supporting structures.

In my prior Patent No. 1,553,037 I have described a skeleton or grid member which consists of battens or laths halved into one 10 another to form a number of cells, which are covered at each side by a lining common to all cells of a grid member. A lining of this kind possesses the drawback, that it cannot brace up and thus secure the correct angular 15 position of the individual cells of each grid member. Further a lining of this considerable size does not fit in such a manner, that a completely closed air compartment is formed in each cell of the grid member, and 20 in case the lining consists of a cement-like material, it will easily break and therefore has to be made of considerable thickness.

According to the present invention a member of a cement-like material and heat-insulating character is inserted into each cell of the grid member in such manner, that a completely closed air compartment is formed in each cell of the grid member. A member of this kind fitted into the cell braces up and 30 thus secures the correct angular position of the individual cells of each grid member.

The building member constructed according to the present invention may be covered with plaster at the outside or veneered with 35 wood or compressed material or covered with any desired material. In case the member is covered with plaster, it is of advantage to allow the insertion members to project somewhat beyond the edges of the wooden skeleton, so that lattice grooves are formed, for 40 anchoring the plaster to the insertion members.

One mode of carrying out the present invention is illustrated by way of example on 45 the accompanying sheet of drawings in which:—

Fig. 1 is a perspective view, partly in section, of a part of a plate constructed according to the present invention.

Fig. 2 is a perspective view of a plate on a reduced scale.

Fig. 3 is a detail view.

In the illustrated embodiment the skeleton consists of laths or battens, the width of

which corresponds to the thickness of the 55 plate to be formed. At the crossing places the laths engage each other in cog-like manner. At both sides the lath 1 is furnished with recesses or slots 2 which, in the illustrated embodiment, are of a depth of about 60 one third of the width of the lath. In this way the lath 1 is, so to say, divided into three longitudinal strips of like width, whereby however the inner strip passes right through from end to end of the lath, while the two 65 outer strips are provided with slots 2 which are spaced apart at suitable distances and extend to the inner strip. The skeleton-walls disposed vertically with respect to the lath 1, are formed by battens 3 and 3', the width of 70 the batten 3 extending over two-thirds of the width of the lath 1 and at one side the batten is provided with slots 4, the depth of which exactly correspond to the width of the inner strip of the lath 1. The batten 3 is pushed 75 into the slots of the lath 1, whereby the batten 3 entirely fills out the slots 2 of the lath, while the slot 4 of the batten 3 is filled out by the inner strip of the lath 1. Now the batten 3' is pushed into the opposite slot of the lath 1. 80 Thus the lath 1 is provided with an inner or middle strip, extending from one end of the lath to the other end thereof, while the batten 3 is furnished with two lateral strips extending from one end of the batten to the 85 other end thereof, one of the said lateral strips being formed by the supplementary batten 3'. The skeleton constructed in this manner cannot become warped or buckle in any direction and thus forms a rigid skeleton for the building slabs, plates or members.

At both outsides the individual cells are closed by insertion members 5 of a fireproof insulating material, such as wood, concrete, slag concrete or the like. A prop or stay 6 95 is disposed diagonally in each cell and supports the two insertion members 5 with respect to one another, so as to form a smooth outer wall-face.

The props or stays 6 correspond in width 100 to the width of the laths reduced by the thickness of the insertion members and the longitudinal edges of the former engage grooves of the latter, so that the props and insertion members form a unit. When manufacturing 105 the plates, the insertion members are secured to one side of the plates, now the props or stays 6 are introduced from the back into

cells and finally the members 5 are inserted at the other side. The outer sides of the laths are chamfered, in order that the insertion members may rest as close as possible 5 against the insertion members of the adjacent cells and the wood is not visible at the outside.

Recesses 7 are provided at the ends of the laths 1, the base of the said recesses extending at an angle and battens or fillets 8, provided with a groove 9, are cemented into the recesses 7 of the laths. The ends of the battens 3 are similarly recessed and provided with fillets. In this manner two grooves are 15 formed right round the plates which on being placed side by side form a hollow space for the reception of a tongue 10 for binding together the plates. The fillets 8 also form anchorage members for the insertion members introduced into the outer cells. The battens 3 and 3' are furnished with grooves 11, which are engaged by an extension of the insertion member 5', and an extension of the insertion member passes underneath the fillet 8, whereby the said member is immovably secured in the cell. The props or stays 6, which are inserted in the cells, supplement themselves to diagonally disposed supporting members, so that in conjunction with the 25 laths 1 and battens 3 they form a skeleton, which passes right through the plates and impart a great strength to the building plate. Owing to the provision of the hollow spaces, formed by the individual cells, the sound is 30 deadened and the heat is isolated and thus 35 the plate, constructed according to the pres-

ent invention, forms an ideal building member for walls, ceilings and roofs.

If desired the props or stays 6 may be dispensed with.

The building plates according to the present invention are fireproof and can be covered with plaster, veneer or the like. In the last event it is of advantage to dispense with the chamfering of the laths of which the skeleton is formed, so that the wood cannot warp owing to the crosswise directed fibres of the wood.

At the edges half-cells are formed, because the end of the skeleton has the appearance of a cell which is cut through in the middle. Thus at all edges a number of depressions are formed which are open at the outside. On erecting the plates, members are inserted in these depressions, which engage the half-cells of the adjacent plates, whereby the plates interengage with one another.

I claim:—

In a building member consisting of a grid member formed by laths halved into one another to constitute a number of cells lined by plates, the provision of a plate of a cement-like material and heat-insulating character for each individual cell, each plate being inserted into the side of each cell, so that a completely closed air compartment is formed in each cell and the plate fitted into the cell braces up and thus secures the correct angular position of the individual cells.

In testimony whereof I affix my signature.

HANS FRITZ.
